(57) **CLAIM**

The ornamental design for an elbow brace, as shown and described.

DESCRIPTION

FIG. 1 is a perspective view of an elbow brace, showing our new design, in use condition.

FIG. 2 is a back elevational view of the elbow brace of FIG. 1.

FIG. 3 is a side elevational view of the elbow brace of FIG. 1.

FIG. 4 is a front elevational view of the elbow brace of FIG. 1; and,

FIG. 5 is a top view of the elbow brace of FIG. 1.

The broken line showing in FIG. 1 is for illustrative purposes only and forms no part of the claimed design.

1 Claim, 4 Drawing Sheets

FIG. 2

FIG. 3

FIG. 4
